UNITED STATES PATENT OFFICE.

WILLIAM G. ALLAN, OF TORONTO, ONTARIO, CANADA, ASSIGNEE, BY MESNE ASSIGNMENTS, TO JOHN P. SCOTT, OF TORONTO, CANADA.

ELECTROLYTIC APPARATUS.

Application filed February 3, 1920, Serial No. 355,991. Renewed May 28, 1923. Serial No. 569,014.

To all whom it may concern:

Be it known that I, WILLIAM G. ALLAN, a subject of the King of Great Britain, residing at Toronto, county of York, Province of Ontario, Canada, have invented certain new and useful Improvements in Electrolytic Apparatus; and I do hereby declare the following to be a full, clear, and exact description of the invention, such as will enable others skilled in the art to which it appertains to make and use the same.

This invention relates to electrolytic apparatus; and it relates more particularly to apparatus suitable for producing oxygen and hydrogen by electrolysis of water.

Heretofore, apparatus for the production of oxygen and hydrogen by electrolysis of water has been of two principal types: first, the so-called pot type or individual cell, which is built as an individual unit, electrically connected to other cells in a battery, but not assembled therewith as a unitary structure; and second, the filter press type of generator, in which a number of individual cells electrically connected in series and a complete battery are mounted and held together in a unitary construction, very much in the manner of the well known filter press, from which this type of generator takes its name. In the so-called pot type of cell or generator, there is ordinarily no special provision for the circulation of electrolyte which may be a solution of either an acid or an alkali, except such as may incidentally occur inside the cell itself due to the thermal and other effects of electrolysis. There are no ducts between cells for circulating the electrolyte and hence no shunt paths for the electric current. Hence nearly all the current is effective in producing the gases, hydrogen and oxygen, from the water; and the current efficiency, as distinguished from the energy efficiency, is relatively very high. There are two separate gas spaces or chambers above the electrolyte level, in which the hydrogen evolved at the cathode and the oxygen evolved at the anode, on opposite sides of a permeable diaphragm between the electrode, collect and are separately conducted away for use or storage.

In the filter press type of generator, special provision is made for circulating the electrolyte. Ordinarily there are no gas spaces above the individual cells, but the hydrogen and oxygen are carried along

with the catholyte and anolyte respectively, through separate offtake ducts forming a part of the circulating system; and the gases do not separate from the accompanying electrolyte until they reach collecting and separating tanks or chambers, of which there are usually two to each battery, one for anolyte and oxygen, and the other for catholyte and hydrogen. After separation of the gases from the electrolyte, the anolyte and catholyte may be separately conducted back to the lower parts of the anode and cathode chambers composing the cells of the battery, or the anolyte and catholyte may commingle before being returned to the cells.

The filter press type of generator, although far more economical of space than the pot type, and usually less expensive to construct for a given output capacity, has been open to certain practical objections, among which may be mentioned shunt current losses, in the electrolyte circulating system, and also somewhat lower purity of the resultant gases, hydrogen and oxygen, due in part to the difficulty of preventing secondary electrolytic action, with consequent evolution of hydrogen and oxygen at various points in the system other than in the anode and cathode compartments proper. Another objection that is sometimes of practical importance is the fact that in generators of this type heretofore proposed, the paths of electrolyte circulation are objectionably long.

The apparatus forming the subject matter of the present invention differs in certain essential respects from both the foregoing types of cells or generators as heretofore constructed, and makes it possible to combine the advantageous features of both types while at the same time avoiding objections characterizing either or both types, and also attaining additional advantages, as will hereinafter appear.

Generally speaking, the apparatus of the present invention superficially resembles the filter press type of generator more than it does the pot type. In the present apparatus however, the path or paths of electrolyte circulation are shorter than in the filter press type, circulation of electrolyte being effected within sub-multiple units or groups of cells, and the number of cells in each group being less than the total number of cells constituting the battery; there

being ordinarily, moreover, no circulation of electrolyte between such units or groups. Furthermore, separate gas spaces for hydrogen and oxygen are provided above the electrolyte level in the half cell compartments. Gas separates from the electrolyte in each cell at the surface of said electrolyte, while electrolyte with or without some gas in suspension or emulsion there-
5 with takes a separate path or paths to collecting and separating chambers provided for each unit or group, the anolyte and catholyte being separately conducted from the cells of the group and being maintained separate throughout, or in any event until after substantially complete separation of the gas from the electrolyte has been effected in the respective separating and collecting tanks or chambers. Gas separating
10 from the electrolyte in said chambers may be combined with gas led from the gas spaces or chambers provided above the electrolyte in the respective anode and cathode compartments, and may be conducted
15 away for storage or immediate use; while the residual electrolyte is conducted back to the cells, most desirably still keeping the anolyte and catholyte separate by the use of individual return ducts for each. In
20 my novel type of generator, therefore, there need be no continuous path of electrically conducting electrolyte from one end of the complete battery of cells to the other, the total number of cells, which may
25 amount to several hundred in a given instance, being subdivided into a plurality of units, say 6, 8, 10 or 12 cells to the unit, for example, or such other number as may be convenient, thus limiting the volt-drop
30 across each unit to a small figure, and largely obviating troubles with insulation and shunt current losses. The arrangement permits each component unit of a battery to be suitably insulated, while at the same time it avoids the high cost and greater floor space required for individual or pot type cells. It permits batteries operating under voltages up to, say 750 volts or the like, to be installed without too
35 great shunt current losses, and with the avoidance of most of the insulating troubles commonly encountered in the filter press type of generator. It also permits circulating the electrolyte entirely within the unit itself for purposes of taking off the evolved gases, as distinguished from the use of outside circulating ducts and offtakes heretofore employed. Moreover, the arrangement lends itself well to accurate regulation of the operating temperature of the electrolyte where such regulation is
40 deemed desirable.

65 A more complete understanding of the invention may be gained from consideration of a typical embodiment thereof shown

in the accompanying drawings and herein-after described in detail and set forth in the appended claims.

In these drawings,

Fig. 1 is a perspective view in elevation 70 showing a typical installation of apparatus within the scope of the invention for generating hydrogen and oxygen from water;

Fig. 2 is a vertical section through one 75 of the units or cell-groups on the line 2-2, of Fig. 4, a portion of the figure at the right being a section on the line 2^a-2^a in order to further illustrate the mounting of 80 the electrodes;

Fig. 3 is a horizontal section on the line 3-3 of Fig. 2; and

Fig. 4 is a vertical section on the line 4-4 of Fig. 2.

Referring first more particularly to Figs. 85 2, 3 and 4, the unit or cell group therein illustrated comprises ten cells in this instance, although the number of cells may of course be more or less than ten, if desired. The component cells of the unit are defined 90 by intermediate separating walls 10, and end walls 10^a, 10^b, which in this instance also constitute electrode-supporting plates; and the cell included between any two consecutive walls 10 is divided into an anode 95 chamber 11, and a cathode chamber 12, by a permeable diaphragm 13 of asbestos cloth or the like. In this instance, the cell walls 10 are formed of sheet metal, such as steel, nickel, nickelized steel, or the like. The margins of the alternating plates 10 and diaphragms 13 are firmly clamped between plane-faced rectangular metal frames 14, which are held firmly clamped together in any suitable manner. In this instance said 100 frames, plates and diaphragms are apertured to accommodate through bolts 15, and the insulating sleeve 16 of any suitable insulating material, such as hard rubber, for example, in which said bolts are encased. The threaded ends of these through bolts 105 carry nuts 17, provided with insulating bushings 18, which nuts can be turned to exert any desired degree of clamping pressure on the assembled parts. Means should 110 be provided for suitably insulating the rectangular frame members 14 from the cell walls 10 and the diaphragms 13. In the particular construction illustrated, a strip 115 of sheet rubber 19 or the like is folded around the inner edge of each frame, covering both flat faces thereof and extending slightly beyond the outer edges of the frame. A similar sheet 20 of insulating material is folded around the outer edge 120 of each cell wall 10 and covers both sides of the marginal portion thereof. A double thickness of insulation is thus provided between each cell wall and cell frame member. For reasons which will appear here- 125

130

inafter, the insulating sheets 20 at the top of the generating unit extend down on both sides of each plate or wall 10 for a considerable distance, terminating at 21 as indicated in Fig. 2; while the sheets 20 on the sides and bottom portions of the unit need extend inward for a distance only slightly beyond the inner edges of the metal frames, as shown.

10 Each of the cell walls or plates 10, with the exception of those forming the end walls 10^a and 10^b, supports a pair of electrode members 22 and 23, mounted on opposite sides of said plate or wall and in good metallic connection with each other, the assemblage constituting a bipolar electrode. In this instance the electrode members 22 are cathodes, while 23 are anodes. The end plate 10^a and its single electrode 23^a constitute a unipolar electrode, an anode in this instance; similarly the end wall 10^b and its single electrode 22^a constitute a unipolar electrode, a cathode in this instance. The electrode members carried by the cell walls 10 may be of any suitable character. In the present instance, where it is ordinarily desired to operate at relatively high current densities and high electrolyte temperatures, and therefore to facilitate disengagement and removal of the evolved gases and to afford opportunity for free circulation of electrolyte, active electrode surfaces of a permeable or foraminous character are most desirable. Accordingly, the active electrode surfaces 24 are of metallic wire mesh, most desirably comprising a plurality of superposed layers or interwoven plies, marginally secured to frames 25 by pins or studs 26, said frames being arranged to space the foraminous electrode surfaces 24 somewhat away from the cell wall or backing plate 10, as indicated at 25^a (Fig. 2), and to maintain said surface substantially in abutment with the diaphragms 13. Each of the frames 25 comprises in this instance a pair of parallel vertical strips or bars which space the foraminous electrode member away from the plate 10, leaving a free vertical passage between the cell wall and the electrode for flow of electrolyte and gas, said passage being open at its upper and lower ends and substantially unobstructed throughout its length. As shown in Fig. 4, the foraminous electrode surfaces thus provided may be mounted on each cell wall or backing plate in the form of panels arranged side by side on said plate and individually secured thereto; but such an arrangement is not essential. Electrode structures of the general character here concerned, and methods of manufacturing the same, form the subject matter of my co-pending applications Serial Nos. 366,988 and 355,989, filed herewith.

65 Suitable means are provided to enable circulation of the electrolyte through the

cells, and for leading off hydrogen and oxygen evolved. In the construction here illustrated the means for electrolyte circulation is embodied inside of the unit or cell group itself; and to a large extent the same thing is true of the means for collecting the evolved gases. At one end of the unit is a chamber or compartment 27 forming an anolyte and oxygen tank or reservoir; while at the opposite end of the unit is the catholyte and hydrogen chamber 28. Said chambers 27 and 28 are included between the respective end walls of the cell group and the walls 27^a and 28^a, the heavily webbed channels 271 constituting frame means to maintain said walls 27^a, 28^a, suitably spaced from the adjacent cell walls and to peripherally enclose said chambers. Each cell of the unit is provided with individual conduit means for supplying anolyte from chamber 27 to the lower part of the anode compartment; and for conducting anolyte from the upper part of the anode compartment to said anolyte chamber. Similarly individual conduit means is provided for supplying catholyte from chamber 28 to the lower part of the cathode compartment of each cell in question, and for conducting catholyte from the upper part of the cathode compartment to the catholyte chamber. In the construction here illustrated, there are provided a lower series of ducts 29 for the electrolyte supply, and an upper series of ducts 30 for return of electrolyte to the respective half-cells or compartments. The number of ducts is the same in each series and is equal to the number of cells comprised in the unit or group, in this instance ten. Each of these ducts is in communication with but one of the cells, and each duct is open at one end to the anolyte chamber, and at the other end to the catholyte chamber. Thus, for example, considering the particular cell comprising the anode compartment A and the cathode compartment C (Fig. 2); it will be observed that the electrolyte supply conduit 29 communicates with the lower part of the anode compartment A through a plurality of peripheral apertures or openings 31; and with the cathode chamber C through similar openings 32. Between these two series of openings and substantially in the same plane as the diaphragm 13, is interposed a baffle disc or partition 33 which should be of suitable non-conducting material, or of metal provided with an insulating covering. This baffle disc or partition divides the electrolyte supply conduit 29 into two separate non-communicating parts, of which the one is in communication with the anolyte chamber 27 through the terminal openings 34, while the other is in communication with the catholyte chamber 28 through openings 35. In a similar manner, the electrolyte return conduit for the cell A C is divided into two distinct

parts by a baffle disc or partition 36, of which the one part opens into anode compartment A, and anolyte chamber 27, through apertures 37 and 38, respectively; while 5 the other opens into the cathode compartment and catholyte chamber through apertures 39 and 40, respectively. The typical individual electrolyte-circulating duct system just described for cell A C is duplicated 10 for each of the other cells in the embodiment of my invention here illustrated, although of course the two sets of apertures, 31, 32, and 37, 39, in each pair of ducts 29, 30, for admitting and discharging electrolyte, are 15 arranged in different planes for the respective cells, as will be clear from inspection of Figs. 3 and 4.

In order to maintain the electrolyte level 41 the same in both the anolyte and catholyte 20 chambers, a duct 42 extends through the lower part of the unit and is open at its ends to the anolyte and catholyte chambers below the liquid level therein; but this balancing duct 42 does not open into any of the cells, 25 and it contains no separating baffle disc or partition. Accordingly it serves to equalize the hydrostatic head in the anolyte and catholyte chambers.

The course of the electrolyte circulation 30 in cell A C (Fig. 2) is indicated by the direction arrows; and the circulation for the other cells is of course the same. The heat developed by the electrolytic action in the cell, together with the copious evolution of 35 gas bubbles (hydrogen and oxygen), causes an upward flow of electrolyte on opposite sides of the diaphragm in the anode and cathode half-cells or compartments. The anolyte and catholyte leave the cell and enter 40 the conduit 30 through the sets of apertures 37 and 39, respectively, on opposite sides of the division or baffle disk 36, the anolyte flowing to the anolyte chamber 27 at the right and the catholyte flowing to the catholyte chamber 28 at the left. The relatively 45 hot anolyte and catholyte thus enter the respective bodies of electrolyte near the upper level 41 thereof, and they lose considerable heat through the conductive chamber walls 27^a and 28^a, by conduction and radiation, when said chamber walls are of heat-conducting material and are not protected by lagging, as in the particular apparatus here 50 illustrated. As the electrolyte cools, it naturally sinks and is replaced by the continual 55 influx of warmer electrolyte from the discharge ends of the conduits 30. As a consequence, the cooler electrolyte in the lower part of the chambers 27 and 28 is continually flowing into the intake ends of the conduits 29, and is entering the lower part of the respective anode and cathode compartments of cell A C, for example, from the 60 portions of said conduit on opposite sides of baffle disc 33 through apertures 31 and 32,

respectively. In the same way anolyte and catholyte circulate through each of the other cells of the unit. Systematic circulation of anolyte and catholyte separately for each cell is therefore attainable merely by the effect 70 of the thermal head; this effect being augmented of course by the mechanical action of the evolved gas bubbles on opposite sides of the cell diaphragms. Under some conditions of operation, however, particularly 75 where it is desired to operate with the electrolyte at a temperature of 160° to 180° F. or higher, the resultant increased conductivity of the electrolyte may so increase the current density as to render it difficult to 80 prevent over-heating by the cumulative effect thus produced, the normal heat radiating capacity of the apparatus being insufficient to bring about a condition of heat 85 equilibrium at the temperature deemed most suitable for operation in a given instance. For this reason, and also for the general purpose of affording means for accurate control and regulation of temperature and the 90 attainment of the proper rapidity of electrolyte circulation, it is sometimes desirable to provide external cooling means for the chamber walls 27^a and 28^a, instead of relying simply upon air cooling. In the construction illustrated, such auxiliary cooling 95 means takes the form of water spraying devices 43, which may be arranged to direct water against said walls at a location near the electrolyte level 41, at which level the electrolyte temperature is highest. This 100 arrangement therefore provides for heat exchange at the greatest temperature differential, with maximum efficiency. Where an installation comprises several generating 105 units or groups of cells, as illustrated in Fig. 1, a single spray pipe between any two units may deliver a double spray curtain to cool the adjacent ends of said units. The water curtains flowing down the walls 27^a and 28^a 110 may be received in suitable gutter means 44 or the like (Fig. 1), discharging at 44^a to a sump, or the water may be deflected away from the cell structure by any suitable means such as water sheds 44^b (Fig. 2), from which troughs or gutters, not shown, may conduct the cooling water to any convenient place of discharge. Water for the cooling sprays 115 may be supplied from a main 45 provided with valved branches 46 leading to the spray devices.

The electrolyte circulation ducts 29 and 30 extend transversely through all the cells, as shown; and the diaphragms and electrode supporting plates or cell division walls must accordingly be suitably apertured to permit 125 this. Provision must also be made for effectively packing the joints thus formed with the said ducts so as to render them liquid and gas tight, while at the same time proper precautions should be taken to pre- 130

vent short-circuiting and to reduce shunt current losses to a minimum, most desirably by systematically insulating the interior of all conduits submerged in or exposed to electrolyte. The arrangement here illustrated for attaining these ends has special advantages from several points of view. The said ducts are composed of or lined with suitable insulating material such as rubber, ebonite, or the like. In the present example, the ducts are composed of insulating material; and instead of being integral, each duct is made up of a plurality of annular segments or rings that can be fitted together to make up the complete duct in a manner more or less analogous to the fitting together of vertebrae in the spine. The rings 47, of which the greater portion of each duct is built up, are blind, that is, they have no peripheral openings. Two rings 48 of each duct are apertured to provide the aforesaid passages 31, 32, or 37, 39, as the case may be, to permit inflow of electrolyte into the particular cell served by any given duct, or to permit outflow of electrolyte from such cell into the duct. Furthermore, the terminal rings 48^a of each duct are apertured, as already pointed out, for discharge of electrolyte into the anolyte or catholyte chamber, or to receive electrolyte therefrom. Each of the duct rings is shouldered as indicated at 49 to accommodate between each pair of rings the entering edges of the diaphragms 13 and backing plates 10. In the case of the backing plates, insulation packing 50, such as sheet rubber or the like, is interposed between the plate and the pair of rings abutting there against. Furthermore, similar insulation may be used where desirable, as indicated at 51, to pack the mating faces of the rings. The necessary pressure to hold the duct rings, packing, etc., in firm assemblage may be applied by tightening nuts 52, working on the threaded extensions of through rods 15, which extend substantially at right angles to the plane bearing faces of the cell frames 14, whereby the end walls or plates 27^a and 28^a may be forced firmly against the ends of said ducts, interposed packing being desirably employed, as at 52^a. The nuts 52 and rods 15 are suitably insulated from said plates by insulating bushings 53.

Some of the hydrogen and oxygen evolved in the cells passes from the cells with the catholyte and anolyte respectively into the corresponding duct 30 and enters the catholyte and anolyte chambers in that way, ample opportunity being afforded for separation of such hydrogen and oxygen from the catholyte and anolyte during their passage downward to the ducts 29, by reason of the considerable hydrostatic head of electrolyte maintained. Such separated gases of course pass into the gas spaces 54 and 55, for

oxygen and hydrogen respectively, above the electrolyte level in said chambers. For the most part, however, the evolved gases pass up around the ducts 30 into the oxygen spaces 56 and hydrogen spaces 57 above the electrolyte level. These spaces 56 and 57 naturally serve as preliminary individual gas collectors for the respective cells, but in them occurs separation of electrolyte entrained by the evolved gases, as will presently appear. From the spaces 56 oxygen passes through channels 58, into an oxygen-collecting chamber 59 above, which extends parallel to the ducts 30. This oxygen-collecting chamber opens into the anolyte-oxygen chamber 27, as indicated at 60; but it is closed at its opposite end and has no communication with the catholyte-hydrogen chamber 28, being separated from the latter by the double wall composed of the end cell wall 10^b and an overlying wall 61, which is most desirably of copper. Similarly, hydrogen passes from spaces 57 above the electrolyte level in the cathode compartments through passages 62, which lead into the hydrogen collecting chamber 63. The hydrogen chamber opens only into the catholyte-hydrogen chamber, and at its opposite end is closed and separated from the anolyte-oxygen chamber by the double wall composed of end cell wall 10^a and wall 64, which is advantageously of a good conducting metal such as copper. Both the oxygen entering space 54 from the oxygen-collecting chamber 59, and also that disengaged from the anolyte discharged into the anolyte chamber, may pass off through an oxygen offtake 65 into oxygen header 66, any entrained liquid which may be mechanically carried over into the header with the oxygen gas being drained off through pipe 67 into an anolyte supply tank 68, from which it may be withdrawn or discharged to waste through a valved outlet 69, or otherwise disposed of. Similarly hydrogen accumulating in gas space 55 above the catholyte is led off through hydrogen offtake 70 into hydrogen header 71, entrained liquid being drained off through drain pipe 72 into receiving tank 73. The receiving tanks 68 and 73 are connected near their lower ends by valved equalizing pipe 74.

The gas collecting chambers 59 and 63 are most desirably formed in a manner analogous to the formation of the electrolyte circulation conduits 29 and 30. In the specific construction here shown, said chambers are formed by a plurality of long rectangular slabs or blocks 75 of insulating material, such as hard rubber, for example, each apertured in such manner that when the blocks or slabs are assembled with the apertures alined with each other and with similar apertures provided in the dia-

phragms 13 and the cell walls, the chambers 59 and 63 are formed. Each of these chambers therefore extends through all the diaphragms, and all but one of the cell walls. 5 The apertures in the cell walls 10 are somewhat larger in cross section than the said collecting compartments, and the resulting annular space left between the edges of the apertures in said plates and the inner wall 10 of each collecting chamber is occupied by a suitable insulating member such as soft rubber gasket 76, which lies between the double insulating sheet 21, before described. Those portions of the asbestos diaphragms 13, situated outside of the edges of the electrodes 22, 23, are rubberized or otherwise rendered impervious and non-conducting, only that portion of each diaphragm included within the dotted boundary line 77 (Fig. 4) being 15 left pervious or permeable by electrolyte. Sheet rubber or the like 78 covers the end wall 10^b where the latter closes the oxygen collecting chamber 59; and insulating gaskets 79 and 80 serve to insulate the edges 20 of double end wall 10^a, 64, from the discharge outlet of said chamber. The hydrogen-collecting chamber 63 is similarly insulated from said end walls. It will be apparent, therefore, that the walls of said gas-collecting chambers are wholly non-conducting, as are also those of the electrolyte ducts. Furthermore, the outer faces of the double end walls 10^a, 64, and 10^b, 61, are covered 25 with insulating material 81. By reason of this use of insulation to protect all surfaces outside of the cells themselves which are exposed directly or indirectly to contact with electrolyte, and which might provide indirect current paths between any anode and 30 cathode in the unit, the shunt current losses are much reduced.

By providing the alternating series 58 and 62 of restricted narrow passages for conducting oxygen and hydrogen, respectively, 35 from the corresponding anode and cathode cell compartments into the collecting chambers 59 and 63, it is possible to prevent the gases, as they rise with considerable velocity from the surface of the electrolyte in the cell compartments, from carrying with them 40 into the gas-collecting chambers such a large amount of the moisture or electrolyte enclosing the said gas bubbles as they would otherwise carry. The tendency is for the major 45 portion of such bubbles to strike the under side of the rectangular frames 75 and to burst, thus releasing the gas and dropping the accompanying moisture for the most part, while the gas thus freed can pass on up 50 through the passages 58 and 62 into the gas-collecting chambers.

Several multi-cell units can be electrically connected together in series by any suitable means. As here shown, bars 82 of copper or the like provide such connection, being se-

cured to the projecting edges of adjacent end cell walls 61. Current supply leads (not shown) may be attached to the walls 61 at the extreme ends of the battery. A pipe 83, entering either electrolyte chamber of each unit, and extending upward outside the unit to a point above the electrolyte level, 55 may serve as a filling intake for replenishing the water supply and also, if desired, as a liquid level gauge. Pipes 84 and 85 lead from the lower part of the electrolyte tanks or chambers, and permit draining the electrolyte therefrom, when necessary. The units may be individually mounted on trucks 60 having rollers 86 running in tracks 87, whereby any unit, after being disconnected from the others, may be moved out and replaced, if desired, by another.

From the foregoing description it will be seen that the present apparatus may be considered to be in effect a compromise between what is commonly known as the filter press type of generator on the one hand, in which the total number of cells in the battery are all clamped together and provided with a common electrolyte circulation system; and, on the other hand, generators commonly referred to as of the pot type, consisting of individual and mechanically independent cells, usually without any system for electrolyte circulation.

Since liquid tightness is an indispensable characteristic of apparatus of this kind, the specific construction shown in the drawings and hereinbefore fully described, is highly advantageous because enabling this result to be achieved in a simple and effective manner. It will be seen that the specific construction illustrated adheres strictly to the principle of providing a series of parallel plane abutment surfaces for the various component parts of the apparatus, such as the cell frames, electrode-supporting plates, diaphragms, etc., all of which may be properly assembled and clamped together by a series of bolts or buckstays extending at right angles to the parallel plane surfaces and situated either within the cell frame border as here illustrated, or optionally and ordinarily less desirably, outside the cell frames. In the latter case, the arrangement may obviously be such that insulation for separating the bolts or buck-stays from the rest of the apparatus is required only at the two ends plates of any given unit or group of cells so clamped together.

The employment of gaskets composed of soft rubber sheet or other suitable material, wherever surface of hard non-resilient material are clamped together, whether these be steel plates, steel frames or hard insulating parts such as duct rings, etc., not only renders the joints between the adjacent surfaces liquid tight and gives the effect of a cushion between the parts, but at the same time the

soft gaskets serve as electrical insulation arranged serially between the assembled parts, thus assisting to prevent to a considerable extent the passage of shunt currents which occasion loss of electrical energy and may lower the purity of the gases. Furthermore, this systematic insulation prevents trouble from grounding.

It will be observed that in the apparatus described, the circulation of electrolyte takes place from each individual half-cell by way of separate upper and lower ducts to an end chamber common to that half cell and to other similar half-cells (say, anode cells) of the group or unit, said upper and lower ducts being wholly unconnected anywhere along their entire length by any electrically conducting path with the electrolyte in any other half-cell until entry is made into the said end-chamber. In this manner, the electrically conducting shunt paths which the electrolyte provides and which necessarily exist where there is a common electrolyte circulating system for a number of cells, are made long and of small area, that is, of comparatively high electrical resistance. In this manner the shunt current losses are substantially reduced.

Where special means such as the water cooling sprays above described are employed for regulation of the electrolyte temperature, it is of course possible to vary the effect of this cooling water curtain in extracting heat from the electrolyte by changing the rate of water flow. This can be done simultaneously and equally for all units in a complete battery by means of a single regulating valve or cock in the supply feed pipe for cooling water, or a separate controlling valve for each group or unit may be provided.

While the diaphragms may be of any material suitable for the purpose, it is considered most desirable to make them of pure asbestos cloth densely woven and having their border or marginal portions impregnated with vulcanized soft flexible rubber or the like. This border, which extends inwardly from the edge to the line 77 as already explained, is very much wider along the top and bottom edges than along the vertical edges because at the top it is necessary to prevent diffusion of gas through the diaphragm above the level of the electrolyte, and also because this part of the diaphragm acts as a resilient gasket between adjacent gas-chamber frames, and also for the adjacent rings of the upper and lower ducts for electrolyte circulation, thus rendering impossible the creepage of gas or electrolyte through the joints at these points. It should be especially noted, however, that in the case of the component rings of the electrolyte circulation ducts, these are not only packed by the rubberized portion of the diaphragms

and the insulation 50, but they are also independently packed by the soft gaskets 51, thus providing a double protection against leakage. This system is also extended in part to the gas ducts or collecting chambers 59 and 63 by means of the gaskets 76; and if desired, similar gaskets might be employed at the joints here shown as packed only by the rubberized diaphragms, although ordinarily this extra precaution is not required. It is obvious that, in the construction shown, the openings through the rubberized parts of the diaphragms for gas chambers, circulation ducts and bolt holes may be punched out accurately by means of dies either before or after the impregnation with rubber has been effected. Other methods of making the diaphragms and other diaphragm materials are of course not excluded.

An important feature of the apparatus here illustrated is that the main path of circulation of the electrolyte is relatively very short. This means that the thermal head and other effects causing circulation to take place are most effectively used. In other words, the resistance to circulation flow is reduced to a minimum and a given thermal head will produce a maximum flow.

It is also to be noted that the construction herein described utilizes the total supplied electrical energy in an especially effective manner. Necessarily, only a part of the supplied electrical energy can be utilized directly for the decomposition of water into hydrogen and oxygen, the remainder of the supplied energy being unavailable directly for this purpose because it degenerates to heat. This heat is utilized in the present instance to reduce the internal cell resistance and also to produce a rapid circulation by thermal head effect, which circulation serves to maintain a more or less equal and constant temperature over the entire unit, serving also more effectively to separate the gases from the electrolyte, which is very necessary where such large volumes of gas are generated in a restricted space. Thus, energy degenerating into heat and becoming unavailable directly for decomposition of water is, in the present apparatus, turned to useful account in an indirect way. In this connection, the importance of the arrangement included in the preferred embodiment here illustrated, whereby it is possible to regulate the temperature as may be desired, becomes increasingly apparent when it is realized that for any particular current through the cells the resultant constant temperature, omitting from consideration for the moment what might be called the artificial cooling, will be that attained at which heat radiated or carried away by convection air currents equals the rate of degradation of electrical energy to heat within

the cells. In the present arrangement the operating temperature is under complete control within wide limits. Nevertheless, it is not to be inferred that the provision of special cooling means is essential in the broader aspects of the invention.

It will be observed that the described construction gives a minimum surface for heat radiation, differing in this respect also from electrolyzers heretofore proposed in which means external to the apparatus may be provided for cooling or temperature regulation. This is an important consideration where the amount of electrical energy degraded to heat is relatively small compared to the total electrical energy supplied, because the most desirable working temperature, say 160° to 180° F. in a typical example, or some other preferred operating temperature or range of temperatures, might not be readily attainable in designs in which the radiation surface is of relatively greater extent. Under some circumstances, even in employing the apparatus described, it may be found desirable to still further reduce the loss of heat by radiation or otherwise from such surfaces as are exposed, by applying exteriorly some suitable form of heat insulation. The present construction offers special advantages in this respect because the four sides and two end walls of the unit are flat and smooth, and substantially free from obstructions such as offtake or intake pipes, etc., thus rendering it a very simple matter to apply heat insulation or lagging, and the covering once applied need not be interfered with until it becomes necessary to entirely dismantle the cell.

The type of apparatus herein disclosed is capable of being operated at relatively high current densities, say from 1 to 3 amperes or more per square inch of projected electrode area.

While a specific embodiment of the invention has been described for the purpose of fully explaining the principles involved, it is not to be inferred that the invention is restricted to the particular details shown.

What I claim is:

1. Electrolytic apparatus comprising, in combination, a plurality of cells, each having an anode chamber and cathode chamber, anolyte container means, catholyte container means, and conduit means whereby each of said anode chambers is individually connected to said anolyte container means, and each of said cathode chambers is individually connected to said catholyte container means, for circulation of anolyte and catholyte, respectively.

2. Electrolytic apparatus comprising, in combination, a plurality of cells, each having an anode chamber and cathode chamber, anolyte container means, catholyte con-

tainer means, said cells and said container means being assembled in a structural unit, and conduit means disposed within the interior of said unit whereby each of said anode chambers and cathode chambers is individually connected, respectively, to said anolyte container means and catholyte container means, for circulation of anolyte and catholyte, respectively. 70

3. Electrolytic apparatus comprising a plurality of plates assembled in suitably spaced and insulated relation to provide a series of cells, electrolyte container means distinct therefrom, and conduit means whereby electrolyte may circulate between 80 said cells and said container means.

4. Electrolytic apparatus comprising a plurality of plates assembled in suitably spaced and insulated relation to provide a series of cells, electrolyte container means 85 and conduit means providing passages through said plates and affording communication between said cells and said container means.

5. Electrolytic apparatus comprising a plurality of plates assembled in suitably spaced and insulated relation to provide a series of cells having anolyte and catholyte containers, respectively, located at opposite ends of said series, and conduit means, 95 whereby anolyte and catholyte, respectively, may circulate between said cells and said containers.

6. Electrolytic apparatus comprising, in combination, a plurality of cells assembled 100 in a multi-cell unit, each cell comprising an anode compartment and a cathode compartment, anolyte container means, catholyte container means and individual intake and offtake ducts separately connecting each of 105 the anode and cathode cell compartments, independently of the others, to said anolyte container means and catholyte container means, respectively.

7. Electrolytic apparatus comprising, in combination, a plurality of flat cells, each having an anode compartment and a cathode compartment, assembled in series as a unit, an anolyte container at one end of the series, a catholyte container at the other end of the series, a plurality of ducts, two for each cell, extending through all the cells and opening into both said anolyte container and said catholyte container, said ducts being arranged in two sets, namely, offtake ducts and intake ducts, and means dividing each duct into two separate parts communicating, respectively, with said anolyte container and said catholyte container, each said anode compartment having communication with the anolyte part of only one offtake duct and one intake duct, and each cathode compartment having communication with the catholyte part of only one offtake duct and one intake duct. 110 115 120 125 130

8. In electrolytic apparatus of the character described, the combination, with a plurality of cells assembled in a unit, of duct means extending through said cells, said duct means comprising a plurality of apertured members situated between the walls of said cells with their apertures registering with cooperating apertures in the cell walls. 5
9. In electrolytic apparatus of the character described, the combination, with a plurality of annular cell frames having plane abutment faces, a plurality of cell walls having plane margins, a plurality of plane-faced diaphragm-supporting members, the cell wall and diaphragm-supporting members being clamped in alternating arrangement between successive pairs of cell frames, and duct means extending through the assemblage and comprising a plurality of co- 10 operating annular members having plane abutment faces. 15
10. In electrolytic apparatus of the character described, the combination, with a cell compartment having a gas collecting space in the upper part thereof, of a gas duct passing through said compartment, and a plurality of restricted passages connecting said compartment with said gas duct. 20
11. In electrolytic apparatus of the character described, the combination, with a cell compartment having a gas collecting space in the upper part thereof, of a gas duct passing through the upper part of said compartment and means permitting passage of gas from said compartment into said duct, but obstructing passage of liquid. 25
12. Electrolytic apparatus comprising, in combination, a plurality of cells assembled in series, an anolyte container at one end of the series, a catholyte container at the other end of the series, a duct system for circulating electrolyte between said containers and said cells, and means for applying cooling liquid to a wall of each said container. 30
13. In electrolytic apparatus, the combination of a plurality of separate members, all having parallel and accurately plane abutment surfaces, cooperating to form a multi-cell unit, substantially as shown and described. 45
14. In electrolytic apparatus, the combination, with cell-forming elements, of duct means composed of a plurality of apertured disks, or blocks of insulating or insulated material, provided with plane abutment surfaces. 50
15. In electrolytic apparatus of the character described, the combination, with a cell compartment having a gas collecting space in the upper part thereof, of a gas offtake duct passing through said compartment and communicating with said gas space, and another offtake duct passing through said compartment below the first mentioned duct and communicating with said compartment. 55
16. In electrolytic apparatus of the character described, the combination, with a cell compartment having a gas collecting space in the upper part thereof, of a gas offtake duct passing through said compartment and communicating with said gas space through passage means permitting free entry of gas from said gas collecting space into said duct but hindering entry of liquid, and another offtake duct passing through said compartment below the first mentioned duct and apertured to permit free passage of liquid thereinto from said compartment. 70
17. In electrolytic apparatus of the character described, the combination with a plurality of assembled cells each having a gas collecting space in the upper part thereof, of gas offtake conduit means extending through said cells and apertured to communicate with said gas collecting spaces, and additional offtake conduit means extending through said cells at a lower level and apertured to receive electrolyte from said cells. 75
18. Electrolytic apparatus comprising, in combination, a plurality of cells, each comprising an anode chamber and a cathode chamber, anolyte container means, catholyte container means, a plurality of offtake conduits and a plurality of return conduits connecting said anode chambers with said anolyte container, and a plurality of offtake conduits and a plurality of return conduits connecting said cathode compartments with said catholyte container. 80
19. In electrolytic apparatus, the combination of a plurality of annular cell frame members, cell walls, and diaphragms, all having substantially parallel plane abutment surfaces, and pressure means acting substantially at right angles to said surfaces, and maintaining the parts operatively assembled. 90
20. In electrolytic apparatus, the combination, with cell-forming elements, of duct means comprising a plurality of disks each having a plurality of apertures and provided with plane end faces. 100
21. In electrolytic apparatus, the combination, with an annular cell frame, of an annular duct member located within the space peripherally bounded by said cell frame and extending in the general direction of the cell frame axis, the length of said duct member being substantially equal to the axial thickness of the cell frame. 110
22. In electrolytic apparatus, the combination, with a casing comprising a plurality of annular casing members having cooperating abutment surfaces, of a plurality of blocks or slabs corresponding in number and thickness with the cell frames and assembled to divide the space within the casing into a lower part and two upper parts extending parallel to the longitudinal axis of the casing, electrode and diaphragm means ar- 120
- 125
- 130

ranged in said lower part to form anode and cathode compartments, the former being in communication with one of said upper parts and the latter being in communication with the other of said upper parts.

23. In electrolyte apparatus, the combination, with a casing comprising annular cell frames and end closure members, all suitably secured together, in combination with electrode and diaphragm means within said casing, and a plurality of duct-forming members structurally separate from said frames and assembled within the inner periphery thereof to provide fluid conduits electrically insulated from said frames.

24. In electrolytic apparatus of the character described, the combination, with a plurality of cells forming a battery, of a plurality of separate duct means, each said 20 separate duct means extending through a plurality of cells in said battery, said duct means being arranged to form separate circulatory systems for said battery.

25. In electrolytic apparatus of the character described, the combination, in a battery comprising cells in sufficient numbers to be counted in a plurality of groups of cells, a plurality of separate duct means, each said 30 separate duct means extending through a plurality of cells in said battery forming a group, said plurality of duct means being arranged to form separate circulatory systems for said groups.

26. Electrolytic apparatus comprising, in combination, a plurality of cells forming a battery and with said cells in sufficient numbers to form a plurality of groups, a separate electrolyte circulatory system for each group, each system comprising duct means 40 extending through the plurality of cells forming the group.

27. Electrolytic apparatus comprising in combination, a plurality of cells forming a battery and with said cells arranged to 45 form a plurality of groups, a separate electrolyte circulatory system for each group, gas collecting chambers for each group, and common mains for collecting the gases from chambers of different groups.

50 28. Electrolytic apparatus comprising, in combination in a battery, a plurality of multi-celled units, a separate circulatory system for each unit including electrolyte container means distinct from said cells of said units.

55 29. Electrolytic apparatus comprising, in combination in a battery, a plurality of multi-celled units, a separate electrolyte circulatory system for each of said units comprising electrolyte containers in each unit,

said containers having outer walls forming opposite boundary walls of said unit, and means positioning said units in said battery to space apart said boundary walls of adjacent units.

65

30. Electrolytic apparatus comprising, in combination in a battery, a plurality of multi-celled units, a separate electrolyte circulatory system for each said unit comprising electrolyte containers in each unit, 70 said containers having outer walls forming opposite boundary walls of said unit, means positioning said units in said battery to space apart said boundary walls of adjacent units, and means for directing a cooling me- 75 dium in contact with said walls.

31. An electrolytic apparatus, comprising a plurality of frame-like separate members all having abutment surfaces, cooperating to form a multi-cell unit, elements engaged between the abutment surfaces, and common and removable means for securing the members and elements together.

80

32. Electrolytic apparatus comprising a plurality of annular frame members arranged end-to-end to form a cell, structurally separate members spaced apart within the cell and dividing the same into a plurality of compartments, electrode elements carried by said dividing members, and diaphragm members alternating with and spaced from said dividing members, and means for holding the parts properly assembled.

85

33. Electrolytic apparatus comprising a plurality of annular frame members arranged end-to-end to form a cell, structurally separate members spaced apart within the cell and dividing the same into a plurality of compartments, electrode elements carried by said dividing members, and diaphragm members alternating with and spaced from said dividing members, 90 said diaphragm members being supported by engagement between frame members, and means for holding the parts properly assembled.

95

34. Electrode apparatus comprising a plurality of annular cell frames having parallel bearing faces, a plurality of diaphragm members spaced apart by said frames and being supported by engagement of the bearing faces, structurally separate electrode members in alternate arrangement relatively to the diaphragms, means for supporting the electrode members, and means for holding the parts properly assembled.

100

In testimony whereof I hereunto affix my signature.

WILLIAM G. ALLAN.
